UNITED STATES PATENT OFFICE.

THOMAS FINNERTY, OF BALTIMORE, MARYLAND.

COAL-CART.

SPECIFICATION forming part of Letters Patent No. 330,217, dated November 10, 1885.

Application filed July 6, 1885. Serial No. 170,751. (No model.)

To all whom it may concern:

Be it known that I, THOMAS FINNERTY, of the city of Baltimore and State of Maryland, have invented certain Improvements in Coal-Carts, of which the following is a specification.

This invention relates to improved means for supporting the upper end of a discharging-chute from a coal-cart, as will hereinafter fully appear.

In the drawings forming a part hereof, Figure I is a side elevation of the principal parts of a coal-cart. Fig. II is a rear view of the same. Figs. III and IV are details of the invention on an enlarged scale.

A is the body of the coal-cart, and B and C the wheels. The doors ordinarily used for the discharge of coal are denoted by a a, and the short spout to which the chute D is generally attached is represented by b. The body is adapted for elevation to give inclination to the chute; but the devices whereby the body is raised are not shown in the drawings, as they form no part of my invention. It happens in some cases that the necessary inclination for the chute to give a proper discharge for the coal cannot be obtained with existing devices. I therefore provide for such a contingency by affixing to the rear end of the cart, or to the side of the same, the hooked rods c, which are adapted to slide in stands d. The hooked rods c are notched, as shown, and

pawls e e are used to hold the rods at any height to which they are raised. The chute D has eyes or hooks, which may be connected to the hooks on the rods c. When the rods c are not in use, they are withdrawn from their stands d and stowed away in any suitable place on the cart. When the hooked rods c are to be attached to the side of the cart, their stands d may be made as shown in Figs. III and IV—that is to say, in one piece—but when the stands are applied over the doors a, as shown in Figs. I and II, they have to be in sections, as represented in those figures.

It will be understood that the hooked rods c are only used when the required elevation of the upper end of the chute cannot be obtained by raising the body.

I claim as my invention—

1. In combination with the body of a coal-cart, a pair of hooked rods attached thereto and adapted for adjustment in height, substantially as and for the purpose specified.

2. In combination with the body of a coal-cart, the stands d, removable hooked and notched bars c, and pawls e, substantially as and for the purpose specified.

his
THOMAS X FINNERTY.
mark.
